(57) **CLAIM**

The ornamental design for pliers with glitter covered handles, as shown and described.

DESCRIPTION

FIG. 1 is a front perspective view of the pliers having glitter covered handles;

FIG. 2 is a side elevational view thereof;

FIG. 3 is a top plan view of the pliers having glitter covered handles;

FIG. 4 is an elevational view of one end thereof;

FIG. 5 is an elevational view of the opposite end of the pliers according to the present invention; and,

FIG. 6 is a bottom plan view of the pliers having glitter covered handles.
